UNITED STATES PATENT OFFICE.

GEORGE H. STANBRIDGE, OF CLEVELAND, OHIO.

BOLT FOR DOORS.

1,108,939.

Specification of Letters Patent. Patented Sept. 1, 1914.

Application filed November 18, 1912. Serial No. 732,022.

To all whom it may concern:

Be it known that I, GEORGE H. STANBRIDGE, a citizen of the United States of America, residing at Cleveland, in the county of Cuyahoga and State of Ohio, have invented certain new and useful Improvements in Bolts for Doors; and I hereby declare the following to be a full, clear, and exact description of the invention, such as will enable others skilled in the art to which it pertains to make and use the same.

This invention relates to new and useful improvements in bolts for doors and particularly to the type of bolts known as panic bolts.

The object of this invention is to provide a bolt of this type for the doors of public buildings, theaters, factories and the like, which will prevent the doors from being opened from the outside but which will permit them to be readily opened from the inside in case of panic.

My invention, therefore, consists in the provision in connection with a bolt suitable for securing a door against being opened of new and improved bolt operating means adapted to be actuated by the pressure of the hand or body of a person.

My invention also consists in the features of construction and combination of parts, described in the specification, pointed out in the claims and illustrated in the accompanying drawings.

In the accompanying drawings Figure 1 is a view in elevation of my device applied to a single door showing the door bolted. Fig. 2 is a similar view showing the door unbolted. Fig. 3 is a section on line 3—3, Fig. 1. Fig. 4 is a section on line 4—4, Fig. 2. Fig. 5 is a view in elevation showing my invention applied to a double door. Fig. 6 is a section on line 6—6, Fig. 5.

Again referring to the drawings, and particularly to Figs. 1 to 4, inclusive, 10 represents the door casing and 11 represents the door. The door is hinged at one side of the casing in the usual manner so as to swing out. On the inner face of the door near the free edge of the door is secured a bolt sheath 15 of the usual form in which is mounted a bolt 16 and in the casing of the door is formed a bolt socket 17 adapted to receive the outer end of the said bolt. The outer end of said bolt 16 is preferably beveled, as shown at 18, to facilitate the entrance of the end of the bolt into the socket and in case the

door is warped or sprung the beveled end enables the bolt to enter the socket and line up the door in its proper position in the casing. On the rear end of the bolt 16 is formed a small projection or lug 19 in which is formed an eye 20. At the side of the bolt sheath 15 is arranged a small support or stand 21 and on this stand is rotatably mounted a bolt lever 22 and one end of said bolt lever 22 is arranged to extend into the eye 20 in the lug 19. On the face of the door near the hinge side thereof is secured a small plate 24 which carries a pair of ears 25.

26 and 27 represent a pair of levers or arms, one of which is preferably somewhat longer than the other and the said levers are pivotally connected at 28 to form a toggle. The end of the shorter lever 26 is pivotally mounted in the ears 25 and the end of the longer lever 27 is provided with an eye 29 adapted to receive the end of the bolt lever 22. The arrangement of the levers is such that when the said levers 26 and 27 lie against or parallel with the surface of the door the bolt lever 22 will be in the position shown in Fig. 2 and the bolt will be withdrawn from its socket, and when the levers 26 and 27 are pulled out from the door so as to stand at an angle to each other and to the door the bolt lever 22 will be thrown around in the opposite direction to the position shown in Fig. 1, and the bolt will be forced into its socket thereby securing the door. The operation of the device will therefore be readily understood. If we assume that the door is bolted then, as before stated, the levers 26 and 27 which form the toggle will stand out from the door, as most clearly shown in Fig. 3. In case of a panic which causes a sudden rush or crowding around the door the person or persons nearest to the door will be pushed or forced against the outwardly projecting levers or toggle and the pressure exerted thereon will cause the levers to be pressed up against the door which will swing around the bolt lever 22 thereby withdrawing the bolt and permitting the door to swing open.

In Figs. 5 and 6 I have shown my invention applied to one of a pair of double doors. As it is customary to use two bolts on a door of this character it is necessary also to duplicate the mechanism heretofore described, and in addition thereto is provided a yoke 30 which has forked ends 31. This yoke 30 bridges the space between the toggles and

the ends of said yoke 30 are operatively connected with the levers of said toggles by means of pins 32 which pass through slots 33 formed in said levers. The operation in this case is the same as before described, except that the yoke member will receive the pressure and will simultaneously cause the operation of both bolt operating mechanisms.

10 What I claim is,—

1. In a device of the character indicated, the combination with a door and its surrounding casing, of a bolt slidably mounted on said door and adapted to engage with said casing so as to hold said door against movement, said bolt being provided with a lug having an eye therein, a support mounted near said bolt, a bolt lever mounted on said support so as to oscillate around a horizontal axis, one end of said lever being adapted to extend into the eye on said bolt and a toggle, one member of said toggle be-

ing hinged to the door at one end, and the other member of said toggle having its free end provided with an eye adapted to receive 25 one end of the bolt lever, for the purpose set forth

2. In a device of the character indicated, the combination with a door and its surrounding casing, of a pair of bolts slidably 30 mounted on said door, a bolt lever pivotally mounted near each bolt and having one end connected with the adjacent bolt, a pair of toggles, one end of each toggle being secured to the door and the other end being secured 35 to the adjacent bolt lever and a yoke operatively connecting said toggles.

In testimony whereof, I sign the foregoing specification, in the presence of two witnesses.

GEORGE H. STANBRIDGE.
